Fig. 10.

Fig. 12.

Figure 11 is a cross-sectional view of a mechanical assembly. It features a central vertical column with various components labeled with numbers: 76, 81, 80, 88, 90, 91, 96, 89, 114, 113, 115, 12, 13, 19, 85, 86, 98, 95, 191, 78, 79, 87, 105, 110, 125, 111, 101, 100, 99, 21a, and 20a. The assembly is partially shaded with diagonal lines. A label 'Fig. 11.' is written in the bottom left corner.

Figure 13 is a side view of a component, showing a cylindrical part with a hatched section. Labels include 76, 125, 110, and 112. A label 'Fig. 13.' is written in the top right corner.

At the bottom right, there is a handwritten signature that reads "August J. Burat" and "BY Topper Topper", with the word "INVENTOR" written above "August J. Burat". Below the signature, the word "ATTORNEYS" is written.

DIRECTION SIGNAL

August F. Burst, Cheektowaga, N. Y.

Application March 24, 1939, Serial No. 263,893

13 Claims. (Cl. 200—59)

This invention relates to a direction signal and more particularly to such a signal which is operatively connected with the steering mechanism of an automobile so that upon turning the steering mechanism a predetermined degree to the left or to the right a corresponding visual direction signal is indicated to the drivers of other vehicles and pedestrians, such signal being cancelled upon the return of the steering mechanism to its normal or straightaway driving position.

One of the objects of the invention is to provide such a signal mechanism in which all danger of public confusion is avoided, an inoperative straightaway zone being provided which permits minor steering movements without giving a signal indication and the movement of the steering mechanism beyond this zone insuring an automatic and correct signal of the direction of movement of the car, such signal being positively cancelled upon return of the steering mechanism to this neutral zone. By this means there is no danger of erroneous and confusing signals being given.

Another object of the invention is to provide manual means for giving either a right or a left signal while the steering mechanism is in its neutral or straightaway zone. This permits the operator of the vehicle to signal his intended movement while standing still, as for a traffic signal, or in advance of the actual intended turn. An important feature of the invention is that the manually signalling means is only operative in the normal or straightaway zone of the steering mechanism and is rendered inoperative and locked against movement when the steering mechanism passes beyond this zone. By this means an erroneous manually given signal is cancelled upon turning the steering wheel beyond the normal or straightaway zone and a correct signalling indication is set up by the automatic signalling mechanism. This interaction of the manual and automatic signalling means therefore avoids the possibility of public confusion in the signalling.

Another object of the invention is to provide such a combined manual and automatic signalling mechanism in which the shift from the manually applied to the automatically applied signal is effected without a flicker, such flicker being confusing to other drivers who might be led to assume a change of intention.

Another aim of the invention is to provide such a signal mechanism which is applicable to a steering member, such as the steering wheel,

which requires a number of turns to swing the steering wheels from the normal straightaway position to the extreme right or left steering position. The signalling system of the present invention is particularly applicable to such steering mechanism and at the same time avoids delicate lost motion devices.

Another object is to provide such a signalling mechanism which can in no way interfere with the steering wheel of the car and hence cannot become a hazard.

Another aim of the invention is to provide such a signalling mechanism which is simple and compact in construction and is composed of few parts which are not liable to get out of order or require replacement; and in which the mechanism can be located immediately under the hub of the steering wheel where the manual control lever is directly accessible and where the casing is inconspicuous and does not interfere with the driving of the car.

In the accompanying drawings:

Fig. 1 is a top plan view of a steering wheel having one form of signalling mechanism associated therewith.

Fig. 2 is a fragmentary vertical enlarged section, through the steering column and steering wheel and the signalling mechanism arranged under the hub of the steering wheel.

Fig. 3 is a horizontal section, taken on line 3—3, Fig. 2.

Fig. 4 is a view similar to Fig. 3 showing the position of the parts after the steering wheel has been turned to the right beyond the normal or straightaway driving position.

Fig. 5 is a vertical section, partly in elevation, of the stationary hub forming part of the signal mechanism.

Fig. 6 is a fragmentary horizontal section, taken on line 6—6, Fig. 2 and showing the contacts for effecting right and left turn signals.

Fig. 7 is a fragmentary vertical section, taken on line 7—7, Fig. 6.

Fig. 8 is a perspective view of a small shoe forming a part of the signalling mechanism.

Fig. 9 is a perspective view of a locking shoe forming part of the signalling mechanism.

Fig. 10 is a top plan view of a steering wheel having a simplified form of signalling mechanism associated therewith.

Fig. 11 is a vertical section lengthwise of the steering post and showing my assembled signalling mechanism in section.

Figs. 12 and 13 are fragmentary horizontal

sections, taken on the correspondingly numbered lines of Fig. 11.

Fig. 14 is a horizontal fragmentary section, through the steering post and hub of the steering wheel, and illustrating the manner in which the manual steering arm is rendered operative and inoperative.

Fig. 15 is a fragmentary vertical section, taken on line 15—15, Fig. 14.

Figs. 16 and 17 are fragmentary views similar to Fig. 14 showing different positions of the parts.

Fig. 18 is a fragmentary enlarged view similar to Fig. 11 showing the manner in which the electrical contact rings are automatically electrically connected to effect the desired signalling indication.

The signalling mechanism forming the subject of the invention is shown as being mounted on the steering post of an automobile and operated either manually or by the hub of the steering wheel under which the mechanism is located. It will be understood, however, that such an arrangement is arbitrary and that the invention could be applied to operate in conjunction with any part of the steering mechanism, especially if automatic signalling only is desired. In the form of the invention shown in Figs. 1-9, the steering wheel 20 is rotatable on the usual stationary post 21 and drives a rotatable column (not shown) housed within the stationary post 30 in the usual manner. The steering mechanism driven by the steering wheel 20 can be of the type which requires several turns of the steering wheel to turn the front wheels of the automobile from their normal or straightaway position to their extreme steering position in either direction. The hub of the steering wheel 20 is shown as being provided in its underside with a radial slot 22, the purpose of which will presently appear.

Below the hub of the steering wheel 20 is arranged a freely rotatable or floating ring 23 which can be made of Bakelite or other suitable insulating material, this ring being rotatably mounted on a stationary hub 24 which is likewise made of Bakelite or other suitable insulating material and is fixed to the stationary steering post 21 so as to be non-rotatable, a set screw 25 being shown as provided for this purpose. The hub 24 is formed to provide an integral upwardly extending inner sleeve 26 which fits around the stationary steering post 21, and an annular upwardly extending outer rim 27 on which the floating ring 23 is rotatably mounted. For this purpose the lower end of the rotatable ring 23 is reduced to provide a groove 28 which receives the upper end of the outer rim 27 of the stationary hub 24.

At its lower end the internal sleeve 26 of the stationary hub 24 carries a wide collector contact ring 30 which is connected by a wire 31 with the positive side of the automobile storage battery B, the other side of the battery being grounded. The outer rim 27 of the stationary hub 24 carries, on its inner side, a pair of collector contact rings 32 and 33, the upper one, 32, of which is connected to the grounded right turn light 34 by a wire 35 and the lower one, 33, of which is connected to the grounded left turn light 36 by a wire 37.

It will be understood that the right and left turn lights 34, 36 can be arranged at the rear or at the front of the car or in both places to indicate to the drivers of other vehicles an intended right or left turn and it will also be under-

stood that if desired dash lamps 38 and 39 can be provided in the lines 35 and 37, these lamps being located where visible to the driver of the automobile and serving to indicate the signal actually being given by the right and left turn lights 34 and 36 to other drivers. It will further be understood that the current from the battery B can be supplied through the usual ignition switch (not shown) of the automobile so that when the ignition is turned off the signal cannot be operated.

The rotatable ring 23 is shown as carrying a vertical rock shaft 45 to the upper end of which is secured a switch arm 46, this switch arm having an upward extension 47 fitting in the radial groove 22 of the steering wheel, and this switch arm also having a knob 48 for the manual operation thereof. The lower end of the rock shaft 45 carries a spring leaf 50 which extends outwardly in opposite directions from the rock shaft 45. One arm of the spring leaf 50 carries a high contact knob 51 and the other arm of the spring leaf 50 carries a low contact knob 52. The high contact knob 51 can be swung into engagement with the upper or right turn collector ring 32 and the lower knob 52 can be swung into engagement with the lower or left turn collector ring 33. Under either of such conditions the other knob engages the wide central collector ring 30.

It will therefore be seen that while the steering wheel is in its normal position the switch mechanism can be manually operated. Thus, the operator can swing the knob 48 to the right, thereby moving the rock shaft 45 to partially rotate the floating ring 23 and at the same time rotating the rock shaft 45 to swing the contact 51 into engagement with the upper collector ring 32 and the lower contact knob 52 into engagement with the central contact ring 30. In so moving the switch arm 46 through the knob 48, the switch arm fulcrums in the radial slot 22 provided in the underside of the steering wheel hub. With such manual movement of the knob 46 to the right, a circuit will be established from the battery B, through wire 31, wide central contact ring 30, lower contact knob 52, spring leaf 50, upper contact knob 51, upper collector ring 32 and through wire 35 and right turn light 34 to ground. This position of the parts is illustrated in Fig. 6.

For automatic operation it will be seen that turning the steering wheel beyond its neutral zone will effect the same result. Thus, on turning the steering wheel to the right the upward extension 47 held in the radial slot 22 causes the switch arm 46 to be thrown to the right and close the circuit through the right turn signal light 34 in the manner just described. Means must, however, be provided for holding this right turn light on during continued movement of the steering wheel and insuring its cancellation when the steering wheel is brought back to its neutral or straightaway zone, since otherwise confusion would result, particularly if the left turn signal could be lighted at the start of the return movement of the steering wheel from its right turned position. Such means also lock the arm 46 against manual operation so as to prevent any manual operation of the signals unless the steering wheel is in its neutral or straightaway zone of operation. For this purpose the inner sleeve 26 of the fixed hub 24 is externally threaded, as indicated at 55, this thread being provided with a flat 56 at its center so as to form,

in effect, a mutilated thread. A small grooved shoe 57 rides on the thread 55, this shoe also having a vertical tongue 58 at its outer side, this tongue riding in a vertical groove 59 in a locking shoe 60. This locking shoe 60 is mounted for radial movement in a recess 61 in the rotatable ring 23 and is yieldingly urged toward the steering post by a pair of helical compression springs 62. This locking shoe 60 carries a locking pin 63 which is moved into engagement with one of two locking recesses 64 and 65 provided in the rock shaft 45. In order to normally hold the switch arm 46 in its neutral position a spring loaded ball 70 is shown as provided in the rotatable ring 23, this spring loaded ball engaging a small recess in the outer side of the rock shaft 45 when the switch arm 46 is in a neutral position. This spring loaded ball 70 therefore prevents the switch arm 46 from accidentally moving from this neutral position due to the throw of the car or other factors.

It will be seen that the free movement of the switch arm 46 is determined by the length of the flat 56 and that at no time can the floating ring 23 be rotated beyond the limit set by the flat 56 unless the switch has been thrown either automatically or by hand to open the circuit through the corresponding signal lamp 34 or 36. In the normal position of the steering wheel and switch arm, the small follower shoe 57 is in engagement with the flat 56 of the thread 55 and hence the compression springs 62 have pushed the locking shoe 60 and this small follower shoe 57 to their extreme inward positions. In such position the locking pin 63 is out of engagement with the rock shaft 45 and hence the switch arm 46 is free to be moved. In this position of the parts the switch arm 46 can therefore be moved either manually, or by turning the steering wheel, either to the right or to the left, this resulting in a corresponding right or left turn signal indication in the signal lights 34 or 36, as previously described. The turning of the steering wheel to, say, the right swings the switch arm 46 to the right, thereby rocking the rock shaft 45 and lighting the right turn signal 34, as previously described. This rotation of the rock shaft 45 moves its locking recess 65 in line with the locking pin 63 of the locking shoe 60. The continued movement of the steering wheel to the right causes the rotatable ring 23 to rotate, this ring being rotated by the upward extension 47 of the switch arm 46 arranged in the radial groove 22. Since the rotatable ring 23 carries the locking shoe 60 and small follower shoe 57, this rotation of the ring 23 to the right causes the small follower shoe 57 to ride off the flat 56 in the thread 55 and onto the unmutilated portion of this thread. This riding of the small follower shoe 57 onto the unmutilated portion of the thread 55 forces the small follower shoe 57 radially outward and this movement of the small follower shoe 57 is transmitted to the locking shoe 60 so as to force the locking pin 63 of this locking shoe into the registering recess 65 of the rock shaft 45, as best illustrated in Fig. 4.

In this position of the parts it will be seen that the switch arm 46 is locked against any independent movement and as, say, the right turn signal 34 has been lighted, this right turn signal will stay lit during the continued swinging of the steering wheel for any distance to the right and also during its return to its normal or straightaway position or zone. During such movement of the steering wheel to its extreme steering po-

sition and back to its neutral zone, the small follower shoe 57 merely rides along the thread 55, its tongue 58 likewise merely riding along the groove 59 in the locking shoe 60 so as to hold the locking pin 63 of this locking shoe 60 in locking engagement with the rock shaft 45. When the steering wheel is returned to its normal position, the small follower shoe 57 reengages the flat 56, which flat permits the small follower shoe 57 to move inwardly. When the small follower shoe 57 so engages the flat 56, the pair of compression springs 62 force the locking shoe 60 and the small follower shoe 57 inwardly so that the locking pin 63 on the locking shoe 60 is moved out of engagement with the recess 65 in the rock shaft 45. This leaves the rock shaft 45 unlocked and hence free to be rocked manually by manipulation of the knob 48 or by operation of the steering wheel as previously described. The continued movement of the steering wheel to its exact normal or straightaway position swings the unlocked switch arm 46 back to its neutral position in which position the contacts 51 and 52 are disengaged from the collector rings, this cancelling the signal previously given.

In the simplified form of the invention shown in Figs. 10-18, the hub of the steering wheel 20a is provided with a pair of small cylindrical holes 75 in its underside, these holes being located on diametrically opposite sides of the hub of the steering wheel. Below the hub of the steering wheel is arranged a rotating or floating ring 76 of Bakelite or other suitable material, this ring being rotatably mounted on a stationary hub 77 which is likewise made of Bakelite or other suitable material and is fixed to the stationary steering post 21a by a set screw 78 or in any other suitable manner. The hub 77 has an integrally formed upwardly extending central sleeve 79 which fits around the steering post 21a and the hub 77 also has an annular upwardly extending outer rim 80 on which the rotatable ring 76 is rotatably mounted. For this purpose the ring 76 is grooved, as indicated at 81, to receive the upper end of the outer sleeve 80. The central sleeve 79 of the hub 77 carries a metal sleeve 85, the major part of which is provided with an external thread 86 and this metal sleeve 85 being provided at its upper end with a cam 87. The outer rim 80 of the hub 77 carries a pair of collector contact rings 88, 89 arranged one above the other and separated by a relatively thin ring 90 of insulating material. An internally threaded nut 91 of insulating material rides on the threads 86 of the metal sleeve 85, the outer peripheral face of this nut being spaced close to the internal faces of the rings 88, 89 and 90. This nut 91 is provided with one or more radial holes 95 in each of which is disposed a small helical metal compression spring 96 which forces two small metal balls 97 and 98 outwardly. The ball 98 is thereby held in electrical contact with the thread 86 of the metal sleeve 85 and the ball 97 is held in contact with either the upper collector contact ring 88, the lower collector contact ring 89 or the intermediate ring 90 of insulating material. The central metal sleeve 85 is connected by a wire 99 with the battery B; the upper collector contact ring 88 is connected by a wire 100 with the grounded left turn signal and the lower collector contact ring 89 is connected by a wire 101 with the grounded right turn signal lamp, all in the same manner as with the form of the invention illustrated in Figs. 1-9.

It will therefore be seen that as the nut 91

is moved to its extreme upward position a circuit will be established from the battery, through wire 99, threaded sleeve 85, ball 97, spring 96, ball 98, upper collector contact ring 88 and through the left turn signal lamp to ground. Similarly in the lowered position of the nut 91 a circuit is established from the threaded metal sleeve 85, through the balls 97 and 98 and intermediate spring 96 to the lower collector contact ring 89 to light the right turn signal lamp.

To rotate the nut 91 in response to the turning movement of the steering wheel 26a, the rotatable ring 76 is provided with a pair of upwardly extending studs 105 which fit into the pair of openings 75 in the underside of the hub of the steering wheel. This rotatable ring 76 likewise carries a pair of downwardly projecting posts 106 which fit in slideways 107 provided in opposite sides of the nut 91. It will therefore be seen that the turning of the steering wheel, through the studs 105, turns the rotatable ring 76 and that the turning of this rotatable ring 76, through the depending posts 106, turns the nut 91, this nut thereby riding up and down the threaded metal sleeve 79 as the steering wheel is turned. The threads of the metal sleeve 85 and the nut 91 are so arranged that turning the steering wheel to the left causes the nut 91 to move upwardly and establish a circuit through the upper collector contact ring 88. Turning the steering wheel to the right from its normal position therefore moves the nut 91 downwardly so as to establish an electrical circuit through the lower collector contact ring 89. It will therefore be seen that turning the steering wheel effects a corresponding signalling indication in the right and left turn signal lamps.

Means are also provided permitting the manual operation of the right and left turn signal lamps during the neutral zone of movement of the steering wheel, the ball 97 in this neutral zone being in contact with the central ring 90 of insulating material so that neither the right nor the left turn signal is illuminated by the mechanism just described. These means also include a lock for preventing manually signalling after the steering wheel has been turned either to the right or to the left beyond this neutral or straightaway steering zone.

The rotatable ring 76 carries a rock shaft 110 to the upper end of which is secured an arm 111 carrying a knob 112. The lower end 113 of the rock shaft 110 is square in cross section and fits a square opening provided in a rock sleeve 114 carried by the nut 91. The upper end of this rock sleeve 114 carries an arm 115 which in turn carries a contact knob 116 adapted to be rotated into engagement with either the threaded metal sleeve 85 or the upper collector contact ring 88. The lower end of the rock sleeve 114 carries an arm 117, this arm in turn carrying a knob 118 which is arranged to engage either the central threaded sleeve 85 or the lower collector contact ring 89.

It will therefore be seen that when the arm 111 is free to be manually swung from one side to the other, the swinging of this arm to the left will cause the upper knob 116 to engage the upper collector contact ring 88 and the lower knob 118 to engage the central threaded sleeve 85. This will establish a circuit from battery, through the central threaded metal ring 85, contact knob 118, arm 117, rock sleeve 114, arm 115, knob 116 and upper collector contact ring to the left turn signal lamp. Swinging the arm 111 to the right

will cause the upper contact knob 116 to engage the central threaded metal sleeve 85 and the lower contact knob 118 to engage the lower collector contact ring 89 so as to illuminate the right turn signal, this position of the parts being illustrated in Fig. 12.

In order to prevent confusion of the public such manual operation of the signal mechanism is permitted only when the steering wheel is in its neutral or straightaway steering zone. When the steering wheel passes beyond this zone, either to the right or to the left, the manual signal arm 111 is swung back to its neutral position and locked in this position until the steering wheel is returned to its normal or straightaway driving zone. For this purpose the inner end of the manual signal arm 111 is provided with a central rounding face 120 which, in the neutral position of the switch arm 111 illustrated by full lines in Fig. 14, is concentric with the axis of the steering column and closely fits the concentric face 121 of the cam 87 when the steering wheel and ring 76 are moved beyond the neutral or straightaway zone of the steering wheel. From the central curving face 120 the edges 122 and 123 of the inner end of the switch arm 111 extend obliquely outwardly, as illustrated in Fig. 14. It will therefore be seen that regardless of the position of the arm 111 it will be swung to its inoperative radial position on encountering the cam 87. Thus, if the manual signal arm 111 has been swung to the right and the steering wheel is then swung to the left, the cam 87 first engages the projection formed by the meeting of the concentric edge 120 and the edge 123 of the arm, as best illustrated in Fig. 16, whereupon continued movement of the steering wheel to the left causes the arm 111 to be swung to an inoperative radial position with its curved edge 120 concentric with and following the salient face of the cam 87. If, on the other hand, the arm 111 has been swung to the right and the steering wheel is turned to the right the inner end of the arm 111 engages the salient portion of the cam 87, as illustrated in Fig. 17, and again causes the arm to be returned to its inoperative radial position on continued movement of the steering wheel to the right. The movement of the steering wheel beyond its normal straightaway driving zone therefore automatically cancels and renders inoperative the manual signalling mechanism, this movement, of course, also setting up the proper automatic signal circuit as previously described. The width of the central insulator ring 90 is preferably such that shifting from, say, a right manually set-up signal to the right automatically set-up signal is effected without a flicker.

It will also be noted that after the steering wheel has been turned beyond its normal straightaway zone the hand lever 111 is rendered inoperative so that confusing signals cannot accidentally or otherwise be given. Thus, on first encountering the cam 87 this lever is brought to a neutral inoperative position. While during the continued turning of the wheel the lever 111 passes beyond this cam and hence could be manipulated until reengaged by the cam on the continued turning of the wheel, such manipulation is ineffective to light the right or left turn signal lights inasmuch as at such time the nut 91 will have been moved either high enough or low enough so that one of the contact knobs 118 or 116 of the hand signalling mechanism necessarily engages the ring 90 of insulating material. Since neither knob 116 nor 118 can engage either the

collector contact ring 88 or 89 under these circumstances it is apparent that a manual signal could not be given, this avoiding all possibility of a confusing or erroneous signal being given during the turning of the steering wheel beyond its normal or straightaway zone.

In order to prevent the hand lever 111 from vibrating or wobbling it is preferably held in its inoperative position by a spring loaded ball 125, which spring loaded ball is suitably mounted in the rotatable ring 76 and engages a shallow recess in the shaft 110 when the lever 111 is in its neutral or inoperative position.

From the foregoing it will be seen that both forms of the invention provide a very simple, low cost and compact mechanism of inconspicuous external appearance which can be readily applied either as an accessory or as standard equipment to the steering mechanism of automobiles and is peculiarly adaptable to modern cars where the steering wheel is turned several revolutions in each direction to effect maximum turning to the right or to the left. It will further be noted that there is no danger of any confusion of the public in the giving of signals since the manual operation can only be effected within a comparatively small zone of movement of the steering wheel in its straightaway position, after which the effect of the manual signalling arm is completely cancelled and taken over by the automatic signalling mechanism. Further, upon turning the steering wheel a predetermined distance either to the left or to the right a corresponding signalling indication is given and this signalling indication is maintained until the steering wheel is brought back to its straightaway zone of operation. It will also be seen that the signalling mechanism in no way interferes with the free steering movement of the steering mechanism and cannot jam or otherwise disable the steering mechanism this being, of course, of primary importance in the prevention of accidents.

I claim as my invention:

1. A directional signal device for vehicles having a steering mechanism including a rotatable part and right and left turn signal lights, comprising a rotatable member separately mounted immediately adjacent said rotatable part and arranged concentric therewith, means interposed between said rotatable part and said rotatable member and compelling said rotatable member to rotate in response to the rotation of said rotatable part, and means actuated jointly by said rotatable member and said rotatable part for operating and maintaining either said right or left turn signal light in operation upon movement of said steering mechanism in a corresponding direction beyond a normal straightaway zone.

2. A directional signal device for vehicles having a steering mechanism including a rotatable part and right and left turn signal lights, comprising a rotatable member separately mounted immediately adjacent said rotatable part and arranged concentric therewith, means interposed between said rotatable part and said rotatable member and compelling said rotatable member to rotate in response to the rotation of said rotatable part, means actuated jointly by said rotatable member and rotatable part for operating either said right or left turn signal light upon movement of said steering mechanism in a corresponding direction beyond a normal straightaway zone, means movable axially of said rotatable part and rotatable member for maintaining either said right or left turn signal light in

operation until the return of said steering mechanism to said normal straightaway zone and means for moving said axially movable means jointly in response to the rotation of said rotatable member and said rotatable part.

3. An electrical directional signal device for vehicles having a steering mechanism including a rotatable part and right and left turn signal lights, comprising a rotatable member separately mounted immediately adjacent said rotatable part and arranged concentric therewith, a manual switch connected with said rotatable member for selectively operating either said right or left turn signal light, means interposed between said rotatable part and said rotatable member and compelling said rotatable member to rotate in response to the rotation of said rotatable part, means actuated jointly by said rotatable member and said rotatable part for operating and maintaining either said right or left turn signal light in operation upon movement of said steering mechanism in a corresponding direction beyond a normal straightaway zone and means actuated by said rotatable part for correcting the effect of said manual switch in the event the setting of the manual switch is inconsistent with the direction of the turn made by said rotatable part.

4. An electrical directional signal device for vehicles having a steering mechanism including a rotatable part and right and left turn signal lights, comprising a stationary member carrying three annular collector contact members, the first of said annular collector contact members being energized and each of the other two being respectively connected with a right or left turn signal light, means movable axially of said annular collector contact members for establishing an electrical connection between said first annular collector contact member and either of said other annular collector contact members and means for moving said last means in response to the movement of said rotatable part of the steering mechanism.

5. An electrical directional signal device for vehicles having a steering mechanism including a rotatable part and right and left turn signal lights, comprising a stationary member carrying three annular collector contact members, the first of said annular collector contact members being energized and each of the other two being respectively connected with a right and left turn signal light, a rotatable member separately mounted on said stationary member immediately adjacent said rotatable part and arranged concentric with said rotatable part and annular collector contact members, means actuated by said rotatable member for establishing an electrical connection between said first annular collector contact member and either of said other annular collector contact members upon movement of said steering mechanism in a corresponding direction beyond a normal straightaway zone, means movable axially of said rotatable member for maintaining said electrical connection until the return of said steering mechanism to said normal straightaway zone and means for moving said axially movable means in response to the rotation of said rotatable member.

6. An electrical directional signal device for vehicles having a steering mechanism including a rotatable part and right and left turn signal lights, comprising a stationary hub having a rigid inner sleeve and a rigid outer sleeve, one of said sleeves carrying an energized annular collector contact member and the other sleeve

carrying a pair of annular collector contact members respectively connected with said right and left turn signal lights, means for electrically connecting said first annular collector contact member with either of said pair of annular collector contact members and means for moving said last means in response to the movement of said rotatable part of the steering mechanism.

7. An electrical directional signal device for vehicles having a steering mechanism including a rotatable part and right and left turn signal lights, comprising a stationary hub having a rigid inner sleeve and a rigid outer sleeve, a helical thread provided on one of said sleeves, one of said sleeves being formed to provide an energized annular collector contact and the other sleeve being formed to provide a pair of annular collector contacts respectively connected with said right and left turn signal lights, a rotatable member mounted on one of said sleeves, a threaded member riding on said helical thread and arranged between said sleeves, means for rotating said threaded member concentric with said sleeves in response to the movement of said rotatable member, and means moved longitudinally by said threaded member for connecting said first annular collector contact with either of said pair of annular collector contacts.

8. An electrical directional signal device for vehicles having a steering mechanism including a rotatable part and right and left turn signal lights, comprising a stationary hub having a rigid inner sleeve and a rigid outer sleeve, one of said sleeves carrying an energized annular collector contact member and the other sleeve carrying a pair of annular collector contact members respectively connected with said right and left turn signal lights, a rotatable member carried by said stationary hub, a manually operable switch carried by said rotatable member and interposed between said inner and outer sleeves and selectively connecting said first annular collector contact member with either of said pair of annular collector contact members, and means actuated by said rotatable part for correcting the effect of said manually operable switch in the event the setting of said manually operable switch is inconsistent with the direction of the turn made by said rotatable part.

9. An electrical directional signal device for vehicles having a steering mechanism including a rotatable part and right and left turn signal lights, comprising a stationary hub having a rigid inner sleeve and a rigid outer sleeve, one of said sleeves carrying an energized annular collector contact member and the other sleeve carrying a pair of annular collector contact members respectively connected with said right and left turn signal lights, a rotatable member mounted at the ends of said sleeves, means arranged between said sleeves and movable axially of said annular collector contact members for electrically connecting said first annular collector contact member with either of said pair of annular collector contact members, means for moving said last means in response to the movement of said rotatable member, means for moving said rotatable member in response to the movement of said rotatable part of the steering mechanism and a manual switch carried by said rotatable member for selectively connecting said first annular collector contact member with either of said pair of annular collector contact members.

10. An electrical directional signal device for

vehicles having a steering mechanism including a rotatable part and right and left turn signal lights, comprising a stationary hub having a rigid inner sleeve and a rigid outer sleeve, one of said sleeves carrying an energized annular collector contact member and the other sleeve carrying a pair of annular collector contact members respectively connected with said right and left turn signal lights, a rotatable member mounted at the ends of said sleeves, means arranged between said sleeves and movable axially of said annular collector contact members for electrically connecting said first annular collector contact member with either of said pair of annular collector contact members, means for moving said last means in response to the movement of said rotatable member, means for moving said rotatable member in response to the movement of said rotatable part of the steering mechanism and a manual switch carried by said rotatable member for selectively connecting said first annular collector contact member with either of said pair of annular collector contact members, comprising a rock shaft carried by said rotatable member and arranged parallel with the axes of said sleeves, an external arm fixed to said rock shaft and electrically connected contacts operated by said rock shaft and engageable alternately with said first annular collector contact member and either of said pair of annular collector contact members.

11. An electrical directional signal device for vehicles having a steering mechanism including a rotatable part and right and left turn signal lights, comprising a stationary hub having a rigid inner sleeve and a rigid outer sleeve, an energized threaded metal sleeve fast to one of said sleeves, a pair of spaced annular collector contact members carried by the other sleeve and connected, respectively, with said right and left turn signal lights, a ring of insulating material between said pair of annular collector contact members, a nut of insulating material carried by said threaded metal sleeve, a pair of electrically connected contacts carried by said nut, one of which contacts permanently engages said threaded metal sleeves and the other of which alternately engages said pair of annular collector contact members and said intermediate ring of insulating material, and means for turning said nut in response to the movement of said rotatable part.

12. An electrical directional signal device for vehicles having a steering mechanism including a rotatable part and right and left turn signal lights, comprising a stationary hub having a rigid inner sleeve and a rigid concentric outer sleeve, an energized threaded metal sleeve fast to one of said sleeves, a pair of spaced annular collector contact members carried by the other sleeve and respectively connected with said right and left turn signal lights, a ring of insulating material between said pair of annular collector contact members, a nut of insulating material carried by said threaded metal sleeve, a pair of electrically connected contacts carried by said nut, one of which contacts permanently engages said threaded metal sleeve and the other of which alternately engages said pair of annular collector contact members and said intermediate ring of insulating material, a ring rotatably fitting the ends of said inner and outer sleeves, means compelling said nut to rotate with said last ring but permitting axial movement

relative thereto, means for rotating said last ring in response to the movement of said rotatable part and a manual switch for selectively connecting said threaded metal sleeve with either of said pair of annular collector contact members, comprising a rock sleeve carried by said nut and having an out of round opening therethrough, a rock shaft carried by said last ring and having an out of round extension fitting said rock sleeve, an external arm for rocking said rock shaft and a pair of electrically connected contacts carried by said rock sleeve and engageable alternately with said threaded metal sleeve and either of said pair of annular collector contact members.

13. A directional signal device for vehicles having a steering mechanism including a rotatable part and right and left turn signal lights, comprising a stationary hub having a rigid inner sleeve and a rigid outer sleeve, one of said sleeves carrying an energized annular collector contact member and the other sleeve carrying a pair of annular collector contact members respectively connected with said right and left turn signal lights, a helical thread provided on one of said sleeves, a rotatable ring mounted at the ends of said sleeves, means for rotating said ring through motion derived from said steering mechanism, a rock shaft carried by said ring and arranged

parallel with said sleeves, an external manually operable arm fast to said rock shaft, said rock shaft being provided with a pair of circumferentially spaced openings, a radially movable locking shoe carried by said rotatable ring and having a pin arranged to enter either of said openings in said rock shaft, electrically connected contacts carried by said rock shaft and connecting said first collector contact member with one of said pair of collector contact members when said locking pin is in register with one of said openings and connecting said first collector contact member with the other of said pair of collector contact members when said pin is in engagement with the other of said openings, a grooved shoe riding along said thread and having a tongue fitting in a longitudinal groove provided in said locking shoe, said grooved shoe when on said thread holding the locking pin of said locking shoe in locking engagement with one of said openings and said thread being provided at its center with a flat permitting inward movement of said grooved shoe and locking shoe to release said locking pin from either of said holes in said rock shaft and spring means yieldingly urging said locking shoe inwardly.

AUGUST F. BURST.
